SUCKER ROD ELEVATOR

James P. Ratigan, Los Angeles, Calif.

Application November 20, 1936, Serial No. 111,876

6 Claims. (Cl. 294—90)

My invention relates to elevators and has particular reference to sucker rod elevators for handling sucker rods for oil well pumps.

In the oil well industry, it is the common practice to employ pumps located in the lowermost portions of the well, the plungers of which pumps are connected by a string of sucker rods to the walking-beam or other apparatus at the top of the well employed for imparting a reciprocating movement to the plunger. To facilitate the handling of the sucker rods as they are lowered into the well, or withdrawn therefrom, the uppermost length of the sucker rod is gripped by a sucker rod elevator by which the string may be lifted or lowered. The sucker rods are usually constructed of lengths of rod material each about 25 to 30 feet long and each having a pin on one end and a box on the other end constituting couplings whereby the sections of sucker rods may be coupled together to form a string. The portion of the sucker rod immediately below the pin or box is usually swedged out to meet the enlargement of the sucker rod necessary to form the pin or box. In certain types of sucker rods the portion of the rod immediately below the pin or box is formed of square cross section, and immediately below it the rod tapers to its normal size and circular cross section, the taper varying with different sizes and makes of rods, rendering it difficult to construct a single rod elevator which will fit the different tapers of the rods.

The types of rod elevators which are in common use usually include a body member having a bore or seat for receiving the rod which communicates with an opening or slot leading to one side of the elevator through which the rod may enter or leave the bore or seat, and a latch or gate is usually provided to extend in some manner across the slot to prevent the sucker rod from escaping from the bore of the elevator. However these gates are not designed to engage the rod while it is in the seat, but merely acts to prevent complete escape of the rod from the elevator, the latches being normally disposed a considerable distance below the upper surface of the elevator so that when a great strain is placed upon the elevator, the tendency of the rod to slip therefrom causes the elevator to twist, which in turn tends to bend the sucker rods immediately below the coupling members thereof.

It is an object of my invention to provide a sucker rod elevator which is simple in its construction, but which will provide gate mechanism readily manipulated to open position to allow the entry of sucker rods into the elevator

but which, when closed, cannot be inadvertently opened, and in which any tendency of the sucker rods to move out of their recess will tend to hold the gates against retractive or opening movement.

Another object of the invention is to provide a sucker rod elevator in which the latch or gate performs two functions, first that of forming a portion of the seat or bore for the opposite or tapered portion of the sucker rod and also acts as a safety latch which will hold the sucker rod snugly against the seat, preventing the tilting or bending of the elevator.

Another object of the invention is to provide a sucker rod elevator having a seat formed in the main body of the elevator and in which the sucker rod is held snugly against the seat by gates readily retractable by manual manipulation to release the rod.

Another object of the invention is to provide a sucker rod elevator of the character set forth in the preceding paragraph, wherein the gate members are adapted to adjust themselves to the taper of the sucker rod.

Another object of the invention is to provide a sucker rod elevator of the character set forth, wherein the latch members extend fully to the upper surface of the elevator body and support the sucker rod substantially throughout the entire depth of the bore or seat.

Another object of the invention is to provide a bail for an elevator having a plurality of small projections extending therefrom for assisting an operator to retain his hold upon the bail without slipping.

Other objects and advantages will be apparent from a study of the following specifications, read in connection with the accompanying drawings, wherein

Fig. 1 is a perspective view of a sucker rod elevator constructed in accordance with my invention;

Fig. 2 is a perspective view of the sucker rod elevator shown in Fig. 1, but viewed from the rear thereof;

Fig. 3 is a plan view of the sucker rod elevator illustrated in Figs. 1 and 2, and partly in section, to illustrate the manner of mounting and operation of the gates;

Fig. 4 is a diagrammatic perspective view of one of the gates and its operating levers; and

Fig. 5 is a top plan view of my sucker rod elevator, illustrating the gates in their retracted or open position.

Referring to the drawings, I have illustrated

my sucker rod elevator as comprising a body member 1 preferably formed as a single piece of metal provided with a pair of trunnions or bosses 2 extending from diametrically opposite sides thereof to engage through eyes or loops 3 formed upon the lower ends of the legs of a U-shaped bail 4 by which the body 1 may be lifted and lowered.

The body 1 is provided with a recess 5 or bore extending vertically therethrough to constitute a seat into which a sucker rod may be received, the diameter of the recess or bore 5 being preferably slightly in excess of the diameter of the particular sucker rod to be manipulated thereby, but of a diameter less than the collars or coupling portions of the sucker rods containing the pins or boxes by which the sucker rods are coupled together. In order to adapt the recess 5 for the reception of sucker rods of varying shapes and to prevent injury to the couplings or enlargements of the sucker rods, I prefer to bevel the upper edge of the recess 5 as indicated at 6.

The recess or bore 5 communicates with the exterior of the body member through a slot 7 which is preferably of such width as to conform substantially with the diameter of the bore or recess 5. That is, the slot 7 should be sufficiently wide to permit the passage therethrough of any sucker rod of a diameter which may be received within the recess or bore 5. The size and shape of this slot is particularly illustrated in Fig. 5. To hold the sucker rods within the recess or bore 5 against accidental displacement or release therefrom, I provide a pair of gates 8 and 9. Each of these gates comprises an elongated rectangular block of metal, particularly illustrated in Fig. 4, the side walls 10 and 11 of which are parallel to each other and the lower wall 12 of which is substantially flat, while the upper wall is formed upon two levels 13 and 14 so that the rearward portion of the block is of slightly less height than the front portion which, as will be hereinafter more fully described, constituted the actual rod-receiving portion of the gate.

The gate blocks 8 and 9 are adapted to reciprocate, respectively, in a pair of slideways 15 and 16 formed in the body member substantially tangential with the circle described by the recess or bore 5. As will be noted particularly from an inspection of Figs. 1, 2 and 3, the slideways 15 and 16 constitute pockets of substantially rectangular cross section extending at an acute angle to the plane of movement of a rod into and out of the recess 5 and in which pockets the blocks are received, the depth of such pockets being considerably in excess of the length of the gate members 8 and 9 so that the gate members may be retracted into such pockets to align the outermost portion of the gates with the side walls of the slot 7 when it is desired to open the slot for passing a rod into or out of the bore 5. It will also be noted that the width of the gate members 8 and 9 in the plane transverse to the movement of the rod into and out of the recess is such that when the gate blocks are projected to their forward positions, one corner of each of them extends approximately halfway across the slot 7 but it will also be noted that in this position the surface of the gate blocks opposite to their point of contact with a rod in the recess still lies within the slideways 15 and 16 so that any pressure exerted by a rod in an attempt to move out of the recess will be transmitted directly to the outer wall of the slideways 15 and 16 and will not effect any longitudinal movement of the gate members nor

produce any bending or twisting stresses thereon. When the rod is in the recess a line from any point of contact of the rod with either of the gate members drawn perpendicularly across the gate member, will meet a point on the outer wall of the slideway. This is an important feature since all prior devices have depended upon the tensile strength and resistance to bending of the gates or gate members themselves, whereas, in my device, all of the forces are transmitted directly to the body of the elevator.

The gate members 8 and 9 are preferably normally urged outwardly of the pockets by means of compression spring 17, one end of which is received in a depression or recess 18 in the rear end of the gate member, while the opposite end bears upon the rear wall 19 of the slideway or pocket. The gate member 8 is adapted to be moved rearwardly by means of a bellcrank lever 20 which is pivoted intermediate its end upon a pivot pin 21. The bellcrank lever 20 extends into and operates within a horizontally extending recess 22 formed within the body member 1 between its upper and lower walls so that one end 23 of the lever 20 projects into the slideway 15 where it is received in a laterally extending opening or bore 24 in the gate member 8.

Be referring particularly to Fig. 2 it will be observed that the upper surface of the body member 1 extends rearwardly thereof as a flange 25 while the bottom wall of the body member extends rearwardly to form a lower flange 26 between which flanges is provided a finger space 27 into which the arm 28 of the bellcrank 20 extends. The outer end of the arm 28 is preferably enlarged as shown in Fig. 2 to form a fingerpiece by which the fingers of the operator's hand may engage and swing the lever about its pivot 21.

It will therefore be observed that by grasping the arm 28 of the lever 20 and moving it toward the center of the body member, the bellcrank lever 20 will slide the gate member 8 rearwardly in its slideway against the force of the spring 17, while a mere release of the lever 20 will allow the spring 17 to return the gate member 8 to its forward or gate-closing position, as shown in Figs. 1, 2 and 3.

It will also be observed from an inspection of Fig. 3 that when the gate is in its forward position the lever 20 abuts the material of the body member 1 surrounding the recess 22 and constitutes a stop or limit for the forward movement of the gate member 8.

The gate member 9 is similarly manipulated by a bellcrank lever 29 pivoted upon a pin 30, the rearward arm 31 of the lever 29 extending also into the finger-space 27 so that an operator may, by engaging one of the levers with his thumb and the other of the levers with his fingers and squeezing them toward each other, simultaneously retract both of the gates 8 and 9, while the mere release of the levers will allow the respective springs to move the gates 8 and 9 toward their closed position.

By referring particularly to Figs. 1 and 2 it will be noted that the slideway 15 extends entirely through the upper surface of the body member 1, throughout a portion of the depth of the slideway to provide a space in which the enlarged forward portion of the gate members 8 and 9 may pass as the gate members are retracted, while the material of the body member on the outer side of the slideways 15 and 16 constitutes a slide abutment or shoulder (as indicated at 32 and 33) against which the gates 8 and 9 bear at all times.

This slide shoulder or abutment prevents the twisting or bending of the gate members 8 and 9 outwardly, irrespective of the pressure exerted by the sucker rod. Thus when the gate members 8 and 9 are in their closed positions, as shown in Figs. 1, 2 and 3, it is impossible for the gates to be opened by a sucker rod held within the bore or recess 5.

The slideways 15 and 16 are preferably disposed at a considerable angle to each other so that the end surfaces 34 and 35 of the gate members 8 and 9 form a considerable angle relative to each other, thus constituting a V-shape to engage a sucker rod as the elevator is swung toward the sucker rod to engage the same. By reason of the angular disposition of these surfaces relative to each other, the elevator may be swung upon a sucker rod by simply swinging the elevator against the sucker rod, the engagement of the sucker rod with the outer surface of the gate members 8 and 9 causing these gate members to be retracted against the force of their springs and allowing the sucker rod to slip past them into the bore or recess 5. Instantly, however, the gate members 8 and 9 will spring back to their closed positions and securely hold the sucker rod in place within the recess 5.

A sucker rod elevator constructed in accordance with the foregoing description may be manufactured with extreme economy since the entire body member, with the bore 5, the recess 7, slideways and pockets 15 and 16 and finger-space 27 and trunnions 2 may be cast in a single operation, while the gate members 8 and 9 may be cast with their recesses 24 and 18 formed therein, requiring no machining of the parts prior to their assembly. Also the levers 20 and 29 may be cast, the only machining operation required being that of boring the necessary opening to receive the pivot pins 21 and 30 for the levers 20 and 29.

In view of the fact that certain types of sucker rods employed are formed with tapered sections below the couplings, the slideways 15 and 16 should be formed of slightly greater width than the width of the gate members 8 and 9 to allow these members considerable latitude of movement out of the truly vertical position to adapt them to accurately engage the particular taper of such tapered sucker rods.

It will also be noted that the bail 4, engaging with the trunnions 2, allows the bail 4 to be folded down relative to the body member 1 so that the entire structure may lie flat on the derrick floor and out of the way of workmen when not in use. If desired, the eyes 3 of the bail 4 may be provided with laterally extending shoulders 36 and the front wall of the body member 1 may be extended, as indicated at 37 and 38, to form abutting shoulders against which the shoulders 36 may bear when the bail is in an upright position relative to the body member. Thus while the bail 4 may be folded down when the bail is not in use, the body member 1 may be swung to a horizontal position when the bails are suspended from the overhead structure of the derrick and will remain in this horizontal position during the time that the tool is in use.

While the bail 4 may be held upon the trunnions 2 by any suitable means, I prefer to form the trunnions 2 with laterally extending keys 39 formed integrally therewith, and to provide eyes 3 of the bail 4 with a keyway 40 through which the keys 39 may pass. The keys 39 are formed near the outer ends of the trunnions 2 and are relatively short so as to provide between them 75

and the side of the bottom member 1 ample space for the reception of the eyes 3 of the bail. The bails are usually flared and may be manufactured with the eyes separated a greater distance than the overall distance between the outer ends of the trunnions 2, and when it is desired to connect the bail 4 with the body member the keys and keyways are placed in alignment and then the legs of the U-shaped bail are squeezed together until the eyes of the bail are brought into contact with the sides of the body 1 and thereafter the rigidity of the bail material will hold the bail securely in place upon the trunnions 2.

When the bail has been placed upon the body 15 of the elevator, the keys will lie beyond the exterior of the eyes of the bail, and hence will prevent any spreading of the ends of the bail as the load is taken up by the bails.

Also, it will be noted that each of the arms 20 of the bail may be provided with a plurality of outstanding "warts" or projections 41 formed thereon which will assist an operator in holding on to the bail, the projections offering gripping surfaces which will prevent slippage of the bail through the hands of the operator.

While I have shown and described the preferred embodiment of my invention, I do not desire to be limited to any of the details of construction shown herein, except as defined in the appended claims.

I claim:

1. In an elevator of the character described, a body having a rod receiving slot and an upwardly facing rod seat at the end of the slot, a pair of latch members projecting into said slot and movable apart and laterally of the slot by engagement with a rod to pass the rod into said end of the slot when the elevator is in substantially its normal vertical axial position, and upwardly facing rod supporting seats on said latch members opposite said body seat.

2. In an elevator of the character described, a body having a rod receiving slot and an upwardly facing rod seat at the end of the slot, a self closing latch comprising a member projecting into said slot and having a portion movable outwardly with relation to the slot by engagement with a rod to pass the rod into said end of the slot when the elevator is in substantially its normal vertical axial position, and an upwardly facing rod supporting seat on said portion of the latch member and opposite said body seat.

3. In a sucker rod elevator, a body member, a recess therein for receiving sucker rods, a slot between said recess and the exterior of said body member through which a sucker rod may pass laterally into said recess, and means for receiving a pair of gate members, one on each side of said slot, said gate members being movable apart and laterally of the slot by engagement with a rod to pass the rod into said recess when the elevator is in substantially its normal vertical axial position, and adapted to bear a portion of the weight of said sucker rod.

4. In a sucker rod elevator, a body member, a recess therein for receiving a sucker rod, a slot extending between said recess and the exterior of said body member through which a sucker rod may pass laterally into said recess, a slideway formed in said body member and extending from said slot at an acute angle to the plane of movement of a rod into and out of said recess, and a gate member reciprocably mounted in said recess and movable laterally of the slot

by engagement with a rod to pass the rod into said recess when the elevator is in substantially its normal vertical axial position and said gate member having a width such that when it projects into said slot substantially all points thereon opposite to points of contact by said rod lie within said slideway, said gate member being adapted to bear a portion of the weight of said sucker rod.

5. In a sucker rod elevator, a body member, 10 a recess therein forming a seat to receive a sucker rod, a slot extending between said recess to the exterior of said body member through which a sucker rod may pass laterally into said recess, a pair of gate members, one on each side 15 of said slot, means mounting said gate members for sliding movement toward and away from each other across said slot to close said slot against the passage of a rod out of said recess, said gate members when in closed position engaging the sucker rod and forming a portion of the sucker rod seat of the elevator and said gate

members being movable apart and laterally of the slot by engagement with a rod to pass the rod into said recess when the elevator is in substantially its normal vertical axial position.

5. In a sucker rod elevator, a body member having an upper surface and a lower surface, a rod-receiving recess extending vertically through said body member and a slot formed in said body member through which a rod may pass into and out of said recess, a pair of slideways formed in said body member, one on each side of said slot and communicating therewith adjacent said recess, a gate member in each of said slideways extending to the upper surface of said body member to form a continuation of the walls of said recess and with said recess forming a rod seat substantially surrounding a rod, said gate members being movable apart and laterally of the slot by engagement with a rod to pass the rod into said recess when the elevator is in substantially its normal vertical axial position.

JAMES P. RATIGAN.
